216,908

LINK CHAIN FOR BRACELETS OR THE LIKE

Samuel N. Cedar, 14 Worcester Road,
Sharon, Mass. 02067

Filed Dec. 5, 1968, Ser. No. 14,809

Term of patent 14 years

Int. Cl. D11—01
U.S. Cl. D45—4

Fig. 1

Fig. 2

Fig. 3

Fig. 4

Fig. 5

FIG. 1 is a perspective view of a link chain for bracelets or the like embodying my new design;

FIG. 2 is a bottom perspective view thereof;

FIG. 3 is an enlarged top plan view of one of the link components;

FIG. 4 is an enlarged bottom plan view of the link component of FIG. 3; and

FIG. 5 is an enlarged side elevation of the link component of FIG. 3.

I claim:

The ornamental design for a link chain for bracelets or the like, substantially as shown.
